[57] CLAIM

The ornamental design for a combined automobile splash guard and display unit, as shown and described.

DESCRIPTION

FIG. 1 is a perspective view of a combined automobile splash guard and display unit showing my new design mounted on the left rear of an automobile which is shown in broken lines for illustrative purposes only and forms no part of the claimed design;

FIG. 2 is an enlarged front elevation view thereof;

FIG. 3 is an enlarged right side elevation view thereof;

FIG. 4 is an enlarged left side elevation view thereof;

FIG. 5 is an enlarged rear elevation view thereof; and

FIG. 6 is an enlarged bottom plan view thereof.
